UNITED STATES PATENT OFFICE

CLARENCE O. BUENGER, OF CHICAGO, ILLINOIS, ASSIGNOR TO HILLS-MCCANNA COMPANY, OF CHICAGO, ILLINOIS, A CORPORATION OF ILLINOIS

LIQUID PUMP

Application filed January 10, 1930. Serial No. 419,768.

My invention relates to liquid pumps, and particularly to variable capacity pumps.

One of the objects of my invention is to provide a positive action for supplying fluid under positive pressure.

Another object of my invention is to provide a single means to drive a duplex pump.

Another object of my invention is to provide a single means to drive a quadruplex pump.

Another object of my invention is to provide means for predetermining the volume of flow through the pump.

Another object of the invention is to provide means for predetermining the volume of flow through the pumps independently of each other.

Another object of my invention is to provide means for setting the pump capacity with a high degree of precision.

Another object of my invention is to provide means for pumping fluids at high pressure from a comparatively small amount of power.

These and other objects will be attained and will be pointed out in the claims.

In the drawings:—

Fig. 1 is a side elevation of the pumping outfit;

Fig. 2 is a plan thereof;

Fig. 3 is a detail view of the pumping element in part section to disclose certain details of construction;

Fig. 4 is a section at the line 4—4 on Fig. 3;

Fig. 5 is a section at the line 5—5 on Fig. 1;

Fig. 6 is a section at the line 6—6 on Fig. 5;

Fig. 7 is a view similar to Fig. 3, showing another arrangement of certain parts; and

Fig. 8 is a partial plan view of the parts shown in Fig. 7.

The pumping outfit as shown in Figs. 1 and 2 consists of a base 1, the two pumps 2 and 3, the motor 4, and a speed-reducing drive 5 of common type which may be understood as consisting of the usual worm and gear drive, but the worm-wheel shaft 6 extends beyond the case of the speed-reducer 5 and has the two crank arms 7—7 for driving the connecting rods 8—8, which operate the

swinging links 2^a and 3^a of the pumps 2 and 3, respectively.

The pumps 2 and 3 have the intake and exhaust connections 2^b—2^c and 3^b—3^c.

Each crank arm 7 is arranged and constructed so as to vary the effective throw of the connecting rod 8 which is pivoted at 7^a. This pivot, which acts as a wrist pin, is mounted on or integral with a cross-head block 7^b slidably mounted in guideways 7^c—7^d of the crank 7. At each end of the guideway are the bearing blocks 7^d, 7^e which furnish journals for an adjusting screw-threaded rod 10. A knurled thumb nut 11 is secured as a pin 12 to the end of the rod 10 which protrudes through the journal block 7^e.

The wrist pin 7^a, so mounted, provides means for operating the pump so that any quantity desired to be delivered within its capacity will be very accurately measured.

Each pump 2 and 3 has its operating swing-link adjustably connected to a shaft 9.

In Figs. 3 and 4 is shown the means of adjustably mounting the swinging arm to a splined shaft 9, the splines 9^a being provided for the arm and similar splines at 9^b provided for a pinion 16, which transmits its motion (derived through the swinging arm and the shaft 9 upon which it is mounted) so to the toothed rack 17, which is securely attached to the upper end of the plunger 15.

It will thus be seen that the rotation of the shaft 6 of the speed-reducer causes reciprocation of the plunger 15 and that any degree of the possible travel of the plunger may be accurately controlled by means of the adjustable wrist pin 7^a which is carried by the cross-head 7^b.

To add durability and long life to the pump, the pinion 16, which is splined to the shaft 9, has teeth cut completely around so that as those in mesh with the rack become worn, a new set may be provided by simply withdrawing the shaft and rotating the pinion. The rack 17 is also mounted on the plunger 15 with a view of easily replacing it by removing a pin 15^a which locks a screw-threaded connection at 17^a.

Journals for the shaft 9 are provided at 18.

and 19, which may be made of special bearing-metal and attached by the screws 18^a and 19^a so as to be easily replaceable.

The pinion 16 shown in Fig. 3 may be utilized for a further use beyond that shown in this figure; in Fig. 7 is shown an arrangement whereby two pumps may be driven by arranging their plunger racks 30—31 at opposite sides of the pinion 16^x. The pump cylinders 32 and 33 may be arranged at each side of a frame 36 which supports the cylinders as well as the pinion 16^x, which is mounted on the shaft 9^x in the housing 36^a. It is to be understood that the housing 36^b contains a pinion similar to 16^x for operating the pumps 34 and 35 and that the swinging arm 37 is duplicated and arranged in all respects beyond that, to operate from opposite ends of a speed-reducing element such as is shown in Fig. 2. Thus, four pumps may be driven from the same motor.

For the purpose of obtaining a continuous flow or approximately so, it is only necessary to join two of the exhaust pipes, as indicated in Fig. 8, the pipe 32^c joining the pipe 33^c at a T fitting 40 and discharging both into a pipe 41.

It is obvious that to produce the same result in an arrangement as indicated in Fig. 3, the crank arms on the speed-reducer may be set at 180° from each other, so that when one pump is exhausting the other is taking in a charge preparatory to discharging it when the first is on its intake stroke.

Since extremely high pressures are expected to be encountered in the cylinder, a very generous stuffing-box is provided at 20, with a gland 21 forced down by the stud-bolts 22—22.

Any one of these pumps may be put out of use by adjusting the cross-head 7^b at the position indicated by dotted lines in Fig. 1, that is, the center of the wrist pin 7^a coincident with the center of the shaft 6, or removing the connecting rod 8 which is held in place by the bolts at both ends thereof.

It will be noted that such moving parts as are subject to greatest wear are made replaceable and apart from the main pump frame 23, so that maintenance is reduced to a minimum.

Many changes and modifications may be made without departing from the spirit of my invention.

I claim:—

1. In a pump mechanism the combination of a motor, a speed reducing unit operatively connected to the motor, said unit having an operating shaft provided with a crank arm, a link connected with said crank arm, a pump plunger and a rack and pinion connection between the plunger and said link whereby the plunger is automatically reciprocated by the reciprocation of said link by said crank arm.

2. In a pump mechanism the combination of a motor, a speed reducing unit operatively connected to the motor, said unit having an operating shaft provided with a crank arm, 70 a link connected with said crank arm, a pump plunger and a rack and pinion connection between the plunger and said link whereby the plunger is automatically reciprocated by the reciprocation of said link by said crank arm, 75 said connection comprising a pinion meshing with a rack on the pump plunger, and a swinging arm on the pinion shaft pivotally connected with said link.

3. The combination with a motor of a speed reducing unit connected with the motor and having a driving shaft provided with a rotating arm, a driving link having a sliding connection with said arm, a swinging arm pivotally connected with the other end of said driving link, a pinion carried by the shaft of said swinging arm, and a pump plunger having a rack meshing with said pinion. 80

4. The combination with a motor of a speed reducing unit connected with the motor and having a driving shaft provided with a rotating arm, a driving link having a sliding connection with said arm, means for adjusting said sliding connection and maintaining same in adjustment, a swinging arm pivotally connected with the other end of said driving link, a pinion carried by the shaft of said swinging arm, and a pump plunger having a rack meshing with said pinion. 85

It witness whereof, I hereunto subscribe my name this 27th day of December, A. D. 100 1929.

CLARENCE O. BUENGER.
